(57) **CLAIM**

The ornamental design for a ceiling fan light kit as shown and described.

DESCRIPTION

FIG. 1 is a bottom perspective view of a ceiling fan light kit in the environment of a ceiling fan.

FIG. 2 is a top perspective view of the ceiling fan light kit of FIG. 1.

FIG. 3 is a top view of the ceiling fan light kit of FIG. 1.

FIG. 4 is a bottom view of the ceiling fan light kit of FIG. 1.

FIG. 5 is a front view of the ceiling fan light kit of FIG. 1.

FIG. 6 is a rear view of the ceiling fan light kit of FIG. 1.

FIG. 7 is a left side view of the ceiling fan light kit of FIG. 1; and,

FIG. 8 is a right side view of the ceiling fan light kit of FIG. 1.

Portions of the ceiling fan light kit and the ceiling fan environment shown in broken lines form no part of the claimed design.
